UNITED STATES PATENT OFFICE.

JOSEPH F. GRAHAM, OF BROOKLYN, NEW YORK.

PYJAMAS.

Application filed October 28, 1921. Serial No. 511,094.

To all whom it may concern:

Be it known that I, JOSEPH F. GRAHAM, a citizen of the United States, and a resident of the city of New York, borough of Brooklyn, county of Kings, and State of New York, have invented certain new and useful Improvements in Pyjamas, of which the following is a full, clear, and exact description.

10 Among the principal objects which the present invention has in view are: To avoid injury and inconvenience in laundering the garments of the character mentioned; to facilitate the manufacture of said garments; 15 to economize in the construction of the garment; and to provide a garment of the character mentioned which is adapted for the service in which it is employed.

Drawings.

Figure 1 is a front view of a pair of pyjamas constructed and arranged in accordance with the present invention.

Figure 2 is a front view showing a modified form of the invention.

Figure 3 is a cross section of the preferred form, the section being taken on the line 3-3 in Fig. 1.

Figure 4 is a section of the modified form, 20 the section being taken as on the line 4-4 in Fig. 2.

Description.

The principal object of the invention may be mentioned as that avoiding the use of 35 buttons for securing the garment in its closed position, which buttons, when the garment is sent to the laundry, interfere with the work in the laundry and become 40 broken or torn therefrom.

With this object in view the garment consists of two duplicated parts, each having a leg portion 9 and a shoulder supported portion. Preferably the shoulder supporting 45 portion referred to is the strip 10, and this is integral with either the waist-band or the leg of the garment. In the preferred form of the garment as shown in Fig. 1 of the drawings there is no waist-band provided, and the strap 10 and the leg 9 are cut from the same piece of material at the same time. Two such pieces, each having the leg 9 and strap 10 are united by a short seam of stitches as indicated by the numeral 55 11. Preferably the short seam is located just forward of the simple portion of the

crotch of the garment. This is the only place where the two pieces constituting the garment are structurally united.

In each portion of the garment the shoulder strap of one leg is so disposed as to 60 to rest over the shoulder of the wearer of the garment on the side opposite the leg of the garment to which the strap is attached. That is to say, the leg 9 that is 65 adjusted to the wearer's left leg has the strap 10 which is carried over the wearer's right shoulder. To this end the strap 10 and portion of the leg 9 of the one section 70 of the garment is passed between the sides of the strap 10 and leg 9 of the other section providing lapped portions or sections 75 of the upper ends of the two leg portions 9-9.

As is usual in constructing pyjamas, the 80 leg portion 9 is to denote width, and the raw edges are united by seams at the inner sides of the leg. Each of the straps 10 may be formed in half sections joined midway 85 between the extremities thereof at the place where the same is superposed on the shoulder of the wearer. If desired the straps may be made continuous and the free end 90 can be sewed to the opposite extremity of the leg portion at the waist-line thereof.

In the modified form of the invention as shown in Figures 2 and 4, there has been substituted for the straps 10, shirt body sections 12 which overlap, as indicated in 95 the drawings, each section being preferably 90 provided with a sleeve 13 of usual shape and construction. The lapping portions 14 and 15 of the two garment sections are preferably arranged to cover the major portion 95 of the body or trunk of the wearer downwardly from points below the neck, thereby providing maximum warmth thereto and to the vitals by means of the doubled walls at the front and rear thereof.

While the present invention has been illustrated and described as adapted to the manufacture of pyjamas, it will be understood that the method of construction and the arrangement of the parts may be employed and incorporated in garments of various characters where pantaloons or trouser legs are to be supported from the shoulders of the wearer without departing from the spirit of the present invention.

Claims.

1. A garment of the class described com-

prising a pair of unit half-garment sections united at the crotch portions thereof only, each section having a leg portion and a shoulder support therefor.

5. 2. A garment of the class described comprising a pair of unit half-garment sections united at the crotch portions thereof only, each section having a leg portion and a shoulder support therefor, the shoulder support in each portion being adapted to engage the shoulder of the wearer at the opposite side of the wearer's body, for which the connected leg portion is intended.

10. 3. A garment of the class described comprising shoulder supporting independent portions adapted to be lapped upon the human body and where the same covers the abdomen of the said body; and means for permanently securing said garment portions in service relation, said means embodying a short stitched seam adjacent the median portion of the crotch only of said garment.

15. 4. A garment of the class described comprising two identically formed sections

shoulder supporting independent portions 25 forming parts of said sections adapted to be lapped upon the human body and where the same covers the abdomen of the said body; and means for permanently securing said garment sections in service relation, said 30 means being arranged so that the garment may be opened in front and in the rear of and upwardly from the median section of the crotch of the said garment.

5. A garment as characterized comprising 35 two integrally formed body and nether sections, and means connecting said sections together in service relation at the crotch portions thereof only.

6. A garment as characterized comprising 40 a pair of identically formed sections, each of said sections consisting of integrally formed body and nether covering portions, and means for permanently securing said sections together in service relation at the 45 median line of the crotch portions thereof only.

JOSEPH F. GRAHAM.
